RAILROAD SWITCH FROG AND ASSEMBLY

Clyde E. Everhart, Wauchula, Fla.

Application March 2, 1938, Serial No. 193,427

2 Claims. (Cl. 246—387)

This invention relates to railroad switch frogs and assemblies. It is well known that the conventional forms of frogs and assemblies are defective in many respects, are unsafe in use and open to certain serious objections, such as that of causing broken wheel flanges and resulting wrecks through the flanges striking or riding upon the usual guard rails, also the side swiping of one train by another as they undertake to pass one another on the main and switch tracks.

It is a prime object of the present invention therefore, to provide a form of switch frog and assembly which will wholly or at least to a very large extent obviate the evils aforesaid incident to the use of the conventional forms of frogs and associated elements.

It is a further object of the invention to provide a railroad switch frog and assembly comprising an elongated, open frame including a pair of side bars spaced apart in a tapered relation, one end of this frame being formed as a pivot head or block and the other end as a frog block, this open frame being located at the track junction in lieu of the regular frog and adjacent lengths of rail, and a tongue rail oscillatably pivoted within the open frame, the same being tapered from end to end, with the larger end pivotally seated at the inner end of the pivot head and the smaller end positioned freely at the inner end of the switch block, and means for simultaneously operating the tongue and conventional switch points of the switch rails for directing a train from the main track to the switch track, or vice versa.

Still a further object of the invention is to provide in combination with connected main and switch railroad tracks including the conventional switch points of main and switch rails, the conventional frog of the central rail crossing being removed together with lengths of the adjacent out-leading rails, an improved frog and operating assembly incorporated in the tracks in lieu of the stated removed parts, the same comprising an elongated, open base frame with side bars spaced suitably apart in a tapered relation along their inner margins, these bars being connected transversely at spaced medial points, at their under sides, by reinforcing cross-slats, and at their ends by a pivot head or block and a frog block respectively, the pivot block being located at the narrow portion or end of the open frame and this end of the frame being mounted in the track-ways with the pivot block abutting the truncated ends of the out-leading rails, with the frog block located at the ends of the rails leading inwardly to the switch points, the frog block being channeled

longitudinally from end to end medially along its upper face for accommodating wheel flanges and providing lateral raised wheel-ways aligned with the balls of the adjacent rails, and a tapered tongue rail oscillatably seated within the open frame with the larger end thereof pivotally mounted in abutting alignment with the inner end of the pivot block and the smaller end freely disposed at the inner end of the frog block, and mechanism for simultaneously operating the tongue rail and switch points for directing trains from one track to the other.

With the foregoing objects and advantages in view, a preferred embodiment of the invention is shown in the accompanying drawings, which constitute a part of this specification, and wherein

Figure 1 is a plan view of sections of a main track and a switch track, showing my improved switch frog and assembly operatively mounted in the trackage in lieu of the conventional forms.

Figure 2 is an enlarged plan view of my improved assembly as mounted in place on the connecting trackage of a main and switch track.

Figure 3 is a longitudinal vertical section on line 3—3 of Fig. 2.

Figure 4 is a side elevation of one end of the assembly.

Figure 5 is a section on the line 5—5 of Figure 2.

Figure 6 is a section on the line 6—6 of Figure 2.

Figure 7 is a section on the line 7—7 of Figure 2.

This invention provides a very novel and efficient assembly of railroad frog and accessories, for a main railroad track represented generally at 5 and a switch track represented generally at 6, all suitably laid of course upon cross-ties 7.

In the carrying out of my invention medial rail sections are cut out from the inner adjacent rails of main and switch tracks to the length required, the conventional frog being also removed, thus leaving transversely aligned rail ends 5a—6a at 40 each end of the vacated space. An elongated open frame or base member, represented generally at 10, is then extended and properly laid upon the cross-ties 7, between these truncated ends of the rails, as clearly shown in Figure 2. This open frame is constructed of iron or steel or other suitable material, and includes a pair of side bars 10a arranged in a spaced and slightly tapered relation side by side and connected medially along their under sides by spaced cross-slats 10b. This frame 50 is closed at its wider end by a frog block 10c which may be formed integrally with the side rails or separately welded or bolted in place as preferred. The outer end of this block abuts the ends of the switch rails 5a—6a leading to the conventional 55

switch points of the trackage and represented in Figure 1 at 5b-5b. This block is channeled out medially and longitudinally at its upper face, from end to end as shown at 10d for accommodating car wheel flanges passing thereover, and thereby providing lateral, raised wheel-ways in exact horizontal alignment with the balls of the adjacent rail ends which converge to the block. This means that the channel of the block is 10 tapered inwardly slightly to correspond with the taper of the converging rails. Thus car wheels may roll smoothly from the rails over this block, with the flanges depending into the channel 10d. This end of the frame 10 is extended laterally at 15 each side to provide a pair of spaced clamps 10e, which reach beyond the frog block and overlie the outer sides of the ends of the two convergent rails 5a-5a, to which they are bolted as shown at 11.

The opposite and narrower end of the open frame 10 is closed by a pivot block or head 10f which likewise may be formed integrally or separately welded or bolted to the side bars. The upper surface of this block is formed on a level with the balls of the adjacent rail ends, and it 25 also is slightly tapered on its side margins to correspond with the taper of the convergent rail ends where it is to be located, that is the rail ends of the tracks 5a-5a at that end of the installation. The frame 10 is laid upon the ties 30 with the outer end of this pivot block 10f abutted against the truncated ends of the rail ends at that point, and the block is preferably formed with an integral, wedge shaped extension 10g which is positioned between the two rail ends 35 and bolted thereto, as clearly shown in Figure 2, at 12.

The inner end of the head or block 10f is undercut as shown at 10h to provide an overlying lip 10i, the margin of which is formed arcuately 40 on a horizontal plane as shown at 10j, for a purpose later to be pointed out. A directional tongue rail 13 is provided, the same being of a length nicely to span the distance between the frog block 10c and the pivot block 10f. This tongue rail is of a uniform thickness from end to end, such that when mounted in place within the open frame 10 upon the cross slats 10b, its upper surface will lie in exact horizontal alignment with the like surfaces of adjacent rail ends or balls. 45 The rail is rounded off at its larger end as shown at 13a so as to smoothly seat within the concaved end of the block 10f, and this end is formed at its under side with the rounded socket 13b adapted to nicely engage the complementally 50 formed head of a heavy stud 14 extended from a cross-piece 10b at the end of the block 10f. This rail is slightly and uniformly tapered from this described larger end to the opposite end 55 13e which is positioned freely at the inner end 60 of the frog block 10c, as shown in Figure 2, where it may be moved laterally across the rail ends 5a-5a at this point, and so as to align with either rail, as desired. Both the extremities of the rail 13 are provided at their under sides with 65 longitudinally extended lugs 13c-13d, the former being arranged to slidably engage the under surface of the lip 10i of the block 10f while the latter similarly engages the under surface of the projected end of an anchor plate 15 which is 70 secured by bolts 16 within the channel 10d of the frog block 10c. Thus the tongue rail 13 firmly yet movably pivoted in place within the open frame 10, and the free end 13e is free to oscillate from side to side from one rail end to another 75 in the operation of the assembly. The side bars

10a of the frame are so arranged and spaced, that in the operative movement of the rail 13 from side to side, it will contact at either side and for the full extent of its length, the side bar 10a at that side of the frame, which bar will brace 5 and sustain it against any lateral strain or thrust that might be imposed upon it by a passing train. It is also to be noted that the relative taper of the side bars 10a, the pivot block 10f, the frog block 10c, and of the tongue rail 13, is 10 such relative to the alignment of the abutting and convergent ends of the central track rails of the main and switch tracks at either end of the assembly, that when the tongue rail 13 is moved fully over against either of the side bars 10a, it 15 will bear against that side bar with the rail itself in exact operative alignment between the switch rail and the central leading out rail of the switch rail of the main track and the main continuing rail of the main track on the other hand, as may be required in the movement of trains over the main track and switch track.

The bars 10a are cut down slightly at their upper sides adjacent the pivot block 10f and for a 25 space inwardly therefrom, as shown at 10k, so as not to interfere with the flanges of car wheels passing over. Otherwise the bars 10a are of a uniform height from end to end, substantially 30 equal to the elevation of the rail 13 and associated rails.

The frame 10 being properly positioned upon the cross-ties 7 and the parts properly assembled in place, the frame is firmly spiked to the ties by means of conventional rail spikes 17 located 35 against the base flanges 10m of the side bars 10a. It is understood of course that in the operation of the assembly, the tongue rail 13 bears at its under side upon the cross-slats 10b, which serve to support it under the weight of passing 40 trains.

An operating lever system is provided, the same comprising a bar 20 slidably extended through loops 21 transversely mounted at the under sides of the bars 10a, adjacent the frog 45 block 10c, and this slide bar carries a pivot pin 22 bolted at 23 to the bar, the upper end of the pin being seated within a socket 13f formed in the under side of the tongue rail 13 at this point.

At one outer end of the bar 20 there is pivot- 50 ally connected by means of a pin 25, a bell crank lever 26, which in turn is pivotally pinned at 27 to a plate 28 secured at 29 to an end of a cross-tie 7. An end of a connecting rod 30 is pivotally pinned at 31 to the outwardly turned arm of the 55 bell crank, and this rod runs thence along the outer side of the switch track to a point laterally adjacent the points of the switch rails 5b-5b. At this point a bar 33 is passed slidably under the rails in conventional manner, and is secured 60 at 34 to the under sides of the switch rails or points which are spaced slightly from the adjacent rails to permit the customary lateral play 65 thereof in the operation of the switch. Another bell crank 35 is pivoted at 36 to a plate 37 secured at 38 to the outer end of a cross-tie 7. One arm of this crank is pivoted at 39 to the extended outer end of the bar 33 and the other arm is similarly pivoted at 40 to the extended end of the connecting rod 30. The opposite end of the bar 70 33 is extended at the outer side of the main track, and a conventional operating lever 42 is pivoted at 43 to this end, the lever itself being pivotally pinned at 44 to a plate 45 mounted on a cross-tie 7 at this point.

The operating levers and connections as above described are so arranged and adjusted that as the switch operating lever 42 is pulled and the switch points move laterally to either side, the 5 free end of the tongue rail 13 will be simultaneously moved to the same side of the assembly, thereby completing the switching movement of the system. It is understood of course that any conventional form of switch stand and locking 10 means, may be added to the assembly described, or connected to the operating lever 42 or any substitution therefor.

The entire assembly is of course to be constructed, dimensioned and proportioned for the 15 smooth working and functioning of the apparatus for the purposes intended and described, and so constructed the same will serve to switch trains from one track to another without any jolting or bumping, as is common with conventional forms of frogs and assemblies, wheel flanges will not be broken on guard rails or frog points, and accidents and wrecks attributable to defective switches or to switches as now commonly used, will be eliminated.

20 While I have herein described and shown certain preferred forms of structure and mechanism for constructing an assembly of the kind referred to, it is understood that I am not to be limited to these precise forms, but that I may vary the 25 same in minor details as expediency may suggest, so as to best provide a practical assembly for the stated purposes, not departing however from the spirit of the invention as defined in the appended claims.

30 I claim:

1. In a device of the kind described, an elongated, open base frame including spaced side bars having their inner adjacent margins extended in a tapered relation corresponding to the tapered 35 relation of the inner rails of a switch track and main track, these bars being connected transversely at spaced points at their under sides by reinforcing cross slats and at their ends by a pivot head and a frog block respectively, the 40 pivot head being located at the narrow end of the open frame which end of the frame is adapted to be mounted in the track-ways with the pivot head abutting the truncated ends of the outleading rails, and the frog block being located 45 at the wider end of the open frame which end of the frame is adapted to be mounted in the trackways with the frog block abutting the truncated end of the inleading rails, the frog block being channeled medially from end to end along

its upper face for accommodating wheel flanges and providing lateral raised wheel ways for alignment with the balls of adjacent rails, there being laterally spaced members extended at either side of the frog block for embracing the outer sides 5 of the adjacent rail ends of the track-way, the opposite end of the frame at the pivot head having an extended wedge portion adapted to position between the adjacent rail ends of the track-way, the inner and under margins of the pivot 10 head and frog block being undercut, a tapered tongue rail oscillatably seated within the open frame with the larger end thereof pivotally mounted in abutting alignment with the inner end of the pivot block and the smaller end freely disposed at the inner end of the frog block, both ends of the said tongue rail having lugs extended at the under sides for engaging the undercuts of the pivot head and frog block, for operatively locking the tongue rail to its seat.

2. In a device of the kind described, an elongated, open base frame including side bars having their inner adjacent margins extended in a tapered relation corresponding to the taper of the inner rails of a switch track assembly, the 25 bars being braced underneath by cross slats, a pivot head closing the end of the frame at the narrowed or convergent end of the side bars and adapted for mounting at the truncated rail ends of the trackage leading outward, a frog block 30 closing the opposite end of the open frame and adapted for positioning at the truncated rail ends of the trackage leading inward, the frog block being channeled medially from end to end on its upper face to provide wheel and flange 35 ways in alignment with the balls of adjacent rails of the trackage wherein the frame is mounted, the inner and under margins of the pivot head and frog block being undercut, a tapered tongue rail oscillatably seated within the open frame with the larger end pivotally mounted in abutting alignment with the inner end of the pivot head and the smaller end freely disposed at the inner end of the frog block, both ends of 40 said tongue rail having lugs extending at the under sides for engaging the undercuts of pivot head and frog block, for operatively locking the tongue rail to its seat, the upper and marginal lines of the frame, side bars of the frame, pivot head and frog block being all dimensioned and 45 designed to correspond with and fit into the trackage wherein the said device is to be incorporated.

CLYDE E. EVERHART.
